CLERICAL RABAT

Melvin A. Miritz, 2714 Gilson St., Racine, Wis.

Filed Aug. 18, 1959, Ser. No. 57,225

Term of patent 14 years

(Cl. D3—8)

FIG. 1

FIG. 4

FIG. 3

FIG. 2

FIG. 1 is a front perspective view of a clerical rabat showing my new design, the back thereof is conventional and unornamented.

FIG. 2 is an enlarged, fragmentary, front elevational view of the clerical rabat shown in FIG. 1.

FIG. 3 is a sectional view taken along the line 3—3 of FIG. 2.

FIG. 4 is a sectional view taken along the line 4—4 of FIG. 2.

I claim:

The ornamental design for a clerical rabat, substantially as shown and described.
